DESIGN FOR A COMBINED ASHTRAY, PIPE KNOCKER, AND PIPE RACK

Arthur H. Nagel, Buffalo, N. Y., assignor to McDonald Products Corporation, Buffalo,
N. Y.

Application April 29, 1939, Serial No. 84,668

Term of patent 14 years

To all whom it may concern:

Be it known that I, Arthur H. Nagel, a citizen of the United States, residing at Buffalo, in the county of Erie and State of New York, have invented a new, original, and ornamental Design for a Combined Ashtray, Pipe Knocker, and Pipe Rack, of which the following is a specification, reference being had to the accompanying drawing, forming part thereof.

Fig. 1 is a plan view of a combined ashtray, pipe knocker, and pipe rack showing my new design.

Fig. 2 is a side elevation with portions broken away and shown in section of the tray as shown in Fig. 1.

I claim:

The ornamental design for a combined ashtray, pipe knocker, and pipe rack, as shown.

ARTHUR H. NAGEL.
